WEARING APPAREL

Arthur Wolf, New York, N. Y.

Application August 16, 1939, Serial No. 290,334

3 Claims. (Cl. 2—131)

My invention relates to wearing apparels, and more particularly to a wearing apparel provided with a collar and/or cuffs permanently attached to the body of the wearing apparel.

5 Although wearing apparels, for example shirts, with permanently attached collar and cuffs have certain advantages over wearing apparels with detachable collar and cuffs, they have the disadvantage that portions of the collar and cuffs, especially the edges of the collar and cuffs, are worn out before the body proper of the apparel is worn out, so that the apparel must be prematurely thrown away.

One object of my invention is to provide a 15 wearing apparel with permanently attached collar and/or cuffs, which are reversible, so that the collar and/or cuffs may be easily reconditioned when portions thereof originally worn at the outside are worn out.

20 In order to carry out my invention into practice, I provide a wearing apparel comprising at least one multi-ply piece of fabric, said piece of fabric having at least two outer plies and one intermediate ply, the inner edges of a first outer 25 ply and of the intermediate ply being permanently attached to the body of the wearing apparel by a permanent connection, the inner edge of the second outer ply being detachably secured to one of the outer sides of the connection between 30 the body of the apparel and said first and intermediate ply by means of a detachable connection, the exposed edges of the three plies of said piece of fabric being permanently connected with each other by permanent connections, and said 35 second outer ply being adapted to be overturned about said exposed edges for securing its inner edge to the other outer side of said connection after the removal of said detachable connection.

40 The above mentioned objects and advantages as well as other objects and advantages of my invention will be more fully disclosed in the following specification reference being had to the accompanying drawings forming part of this 45 specification, in which:

Fig. 1 is a perspective view of a portion of a shirt with a permanently attached reversible collar,

Fig. 2 is a fragmentary elevational view of the 50 upper portion of the shirt with the collar, said view showing the inner face of the collar with the latter opened out to show the contour thereof, portions of the collar and neck-band being broken away to show concealed portions of the 55 collar and neck-band,

Fig. 3 is a cross-section taken on line 3—3 of Fig. 2,

Figs. 4—6 are cross-sections similar to that shown in Fig. 3, illustrating various positions of one outer ply of the collar during the reversion 5 thereof,

Fig. 7 is a fragmentary elevational view of the left hand portion of a further embodiment of the upper portion of a shirt with a collar attached thereto,

Fig. 8 is a cross-section taken on line 8—8 of Fig. 7,

Fig. 9 is a fragmentary elevational view of the left hand portion of still a further embodiment of the upper portion of a shirt with a collar 15 attached thereto,

Fig. 10 is a cross-section taken on line 10—10 of Fig. 9,

Fig. 11 is a perspective view of a portion of the sleeve of a shirt with a permanently attached 20 reversible cuff,

Fig. 12 is a fragmentary elevational view of the sleeve with the cuff, said view showing the inner face of the cuff with the latter opened out to show the contour thereof, portions of the cuff 25 being broken away to show concealed portions thereof,

Fig. 13 is a cross-section taken on line 13—13 of Fig. 12,

Figs. 14—16 are cross-sections similar to that 30 shown in Fig. 13, illustrating various positions of one outer ply of the cuff during the reversion thereof, and

Fig. 17 is a cross-sectional view of a different embodiment of a reversible cuff.

Referring now to Figs. 1—3, 20 generally indicates the reversible collar, 22 generally indicates the neck-band, and 24 generally indicates the shirt. The reversible collar 20 comprises three plies made of the same material, i. e. the first 40 outer ply 26, the intermediate ply 28, and the second outer ply 30. The exposed edges 32, 34, 36 of said plies are permanently connected with each other by permanent seams 38. The inner edges 40, 42, 44 of the plies of the collar are attached to the neck-band as will be described hereinafter. The neck-band 22 comprises the two outer layers 46 and 48 and the stiffening lining 50. The lining 50 is embraced by the inturned hems of the outer layer 48. The lower edges 50 of the layers 46 and 48 and the lining 50 are permanently secured to the upper portion of the shirt 24 by means of a permanent seam 52. The stiffening lining 50 could be omitted, if desired. The inner edges 40 and 42 of the outer ply 26 and 55

the intermediate ply 28 of the collar are inserted in the space between the upper edges of the layers 46 and 48 of the neck-band and are permanently secured thereto by means of a permanent seam 54. The inner edge 44 of the second outer ply 30 of the collar has an inturned hem 56, and a rip band 58 is placed between said hem 56 and the outer layer 48 of the neck-band. The stitches of a removable seam or rip seam 60 pass 10 through the inner edge 44 of the outer ply 30, the rip band 58 and the inner edges of the plies 26 and 28 and the upper edges of the layers 46 and 48. Thus, the inner edge 44 of the second outer ply 30 of the collar is detachably secured to one of the outer sides of the connection 15 between the neck-band 22 and the first outer ply 26 and the intermediate ply 28 of the collar 20. Preferably, the rip band is provided with a loop 62 projecting from the inner edge 44 of the 20 ply 30. The stitches of the removable seam 60 do not pass through said loop 62. Said loop facilitates the gripping of the rip band, when the removable seam shall be ripped by a pulling out of the rip band.

25 Preferably all of the three plies 26, 28, 30 of the collar 20 are provided with decorative blind seams 64, 66, 68 near the exposed edges 32, 34, 36.

If desired, a stiffening lining similar to the lining 59 of the neck-band may be arranged between the first outer ply 26 and the intermediate ply 28 of the collar.

Fig. 1 illustrates the normal position of the collar 20 in use. The same position is indicated in Fig. 3 by dash and dotted lines. As pointed out above, the inner edges of the plies 26 and 28 of the collar 20 are permanently secured to the two layers 46, 48 of the neck-band 22 embracing same, and the inner edge of the ply 30 of the collar is detachably secured to the outside of the neck-band. If, for any reason, a reversion of the collar is desired, the following steps are carried out: The collar and the upper portion of the shirt are opened out as shown in Fig. 2. This position is indicated in Fig. 3 by the solid lines. Then the loop 62 of the rip band 58 is gripped by the fingers of a hand, and the rip band is pulled out, whereby the removable seam 60 is ripped and the connection between the inner edge 44 of the ply 30 and the neck-band 22 is destroyed as shown in Fig. 4. The permanent seam 54, however, maintains the attachment of the plies 26 and 28 to the neck-band. Now, the hem 56 is turned into the position 56' (see Fig. 5), and the entire ply 30 is overturned about the 35 exposed edges 32, 34, 36 in the direction of the arrow A (see Fig. 5), until it reaches the position shown in Fig. 6, in which its inner edge 44 contacts the other outside of the neck-band 22. Then, the ply 30 is secured in its new position 60 by a seam 70 which may be a permanent one. For use, the reverted collar is brought into the position shown in dash and dotted lines in Fig. 6. As will be apparent, the reverted collar has the same appearance as the collar shown in Fig. 65 1, as the ply 30 replacing the ply 26 has also a decorative blind seam, the seam 68, near its exposed edges. Moreover, the reverted collar has the appearance of a new collar without any worn out portions. The ply 30 covers the worn out ply 26 70 and its fresh surface 31 previously being inside the collar 20 (see Fig. 5) is now on the outside thereof as shown in Fig. 6. The ply 26 now becomes the intermediate ply, and the previously protected intermediate ply 28 becomes an outer 75 ply.

While Figs. 1-6 show a reversible collar permanently attached to the neck-band forming a part of the shirt, a detachable collar could be rendered reversible in the same manner. In such a case the neck-band would form a part of the 5 collar.

Figs. 7 and 8 show a different embodiment of a reversible collar 20 permanently attached to the shirt 24. In this event, a special neck-band is omitted; the so-called neck-band forms an 10 integral part of the plies of the collar 20. The inner edges of the outer ply 26 and the intermediate ply 28 embrace the upper portion of the shirt 24 and are permanently secured thereto by a permanent seam. The inner edge of the reversible outer ply 30 is detachably secured to the intermediate ply 28 by a rip band 58 and rip seam. The button 23 and the button hole in the other side of the collar (not shown) are arranged on the lower portion of the collar. The 20 exposed edges 32, 34 of the plies of the collar are connected with each other by permanent seams. The collar may be reverted in the same manner as described in connection with Figs. 3-6.

The embodiment of a reversible collar 20 shown 25 in Figs. 9 and 10 is similar to that shown in Figs. 7 and 8 with the only exception, that the lower portion of the collar does not have the extension 25 shown in Fig. 7, and that the button 23 and the button hole (not shown) are arranged on the 30 upper portion of the shirt 24.

Figs. 11-13 illustrate a sleeve of an apparel provided with a permanently attached cuff, which is reversible according to the same principle as 35 pointed out above in connection with the description of the collar. The cuff 120 comprises three plies, i. e. the outer plies 126, 130 and the intermediate ply 128. All of the plies are made of the same material and are provided with blind seams. The exposed edges 132, 134, 136 of said 40 three plies are permanently connected with each other by permanent seams 138. A stiffening lining not shown in the drawings may be inserted between the plies 126 and 128. The inner edges 140 and 142 of the plies 126 and 128 embrace 45 the fabric 124 of the sleeve and are permanently secured thereto by a permanent seam 154. A rip band 158 is placed between the inner edges 142 and 144 of the plies 128 and 130, and the ply 130 is detachably secured to the ply 128 by a removable seam or rip seam 160, the stitches of which pass through the rip band. Each ply is provided with two pairs of button holes 172, 174, 176 and the plies 126 and 128 are connected with each other at the button holes 172, 174, by the 55 button hole stitches or eyelet stitches 178 passing through both plies. The button hole stitches 180 of the button holes 176 of the ply 130, however, do not pass through the plies 126 and 128, so that the ply 130 may be overturned about the 60 exposed edges 132, 134, 136 for a reversion of the cuff, after the removable seam 150 has been ripped by pulling out the rip band 158. The individual steps of the reversion of the cuff are illustrated in Figs. 13-16 and do not need further explanation, as they are the same as the steps for the reversion of the collar illustrated in Figs. 3-6. In the reverted cuff, the ply 130 lies on the ply 126, which now is an intermediate ply. The ply 130 is secured in its new position by means of a seam 170. After the reversion of the cuff, the latter is folded in the usual manner as shown in Fig. 11.

Fig. 17 illustrates a further embodiment of my 70 reversible cuff. The ply 130' is shorter than the 75

plies 126 and 128, so that only one pair of button holes 176 is needed for the ply 130'. The ply 130' is detachably secured to the ply 128 at a place spaced from the inner edge of the ply 128, said 5 place being below the upper pair of button holes 172, 174 of the plies 126, 128 as seen in Fig. 17.

Figs. 11-17 illustrate a cuff permanently attached to a sleeve. If desired, however, a separate reversible cuff could be constructed according to the same principle. In this case, however, the piece of fabric indicated by 124 in Figs. 10 13-17 would form a separate strip to be attached to the sleeve of the shirt and would not be integral with the shirt.

15 Instead of the rip band and rip seam, any other type of an easily removable or detachable connection may be used for the detachable securing of the ply 30 or 130 respectively, and I do not wish to be limited to the use of the rip 20 band and rip seam shown in the drawings.

I have described preferred embodiments of my invention, but it is clear that numerous changes and omissions may be made without departing from the spirit of my invention. For 25 example the reversible collar and/or cuffs could be attached to other apparels than shirts, for example blouses.

What I claim is:

1. In a wearing apparel, a multi-ply collar, said 30 collar consisting of at least two outer plies and one intermediate ply, said outer plies and said intermediate ply consisting of the same material, the inner edges of a first outer ply and of the intermediate ply embracing an edge of the fabric 35 of the apparel and being permanently secured to said fabric by a permanent seam, the inner edge of the second outer ply being detachably secured to the intermediate ply by a removable seam, the exposed edges of the three plies of the collar being 40 permanently connected with each other by permanent seams, and said second outer ply be-

ing adapted to be overturned about said exposed edges for securing its inner edge to the first outer ply after the removal of said removable seam.

2. In a wearing apparel, a neck-band, said neck-band embodying at least two layers, and a 5 multi-ply collar, said collar consisting of at least two outer plies and one intermediate ply, said outer plies and said intermediate ply consisting of the same material, the inner edges of a first outer ply and of the intermediate ply being 10 embraced by said two layers of the neck-band and being permanently secured thereto by a permanent seam, the inner edge of the second outer ply being detachably secured to the outside of one of said layers of the neck-band by a removable 15 seam, the exposed edges of the three plies of said collar being permanently connected with each other by permanent seams, and said second outer ply being adapted to be overturned about said exposed edges for securing its inner edge to 20 the outside of the other layer of the neck-band after the removal of said removable seam.

3. A reversible collar comprising a neck-band, and at least three plies made of the same material, said neck-band embodying at least two layers, the inner edges of a first outer ply and of the intermediate ply of the collar being embraced by said two layers of the neck-band and being permanently secured thereto by a permanent seam, the inner edge of the second outer 25 ply of the collar being detachably secured to the outside of one of said layers of the neck-band by a removable seam, the exposed edges of the three plies of said collar being permanently connected with each other by permanent seams, and 30 said second outer ply being adapted to be overturned about said exposed edges for securing its inner edge to the outside of the other layer of the neck-band after the removal of said removable seam. 35

40 ARTHUR WOLF.
